UNITED STATES PATENT OFFICE

172,320

SCARF

Robert L. Tucker, Jr., Tallassee, Ala., assignor to Robert Tucker Enterprises, Inc., Tallassee, Ala.,
a corporation of Alabama

Application November 4, 1953, Serial No. 27,448

Term of patent 7 years

(Cl. D3—12)

To all whom it may concern:

Be it known that I, Robert L. Tucker, Jr., a citizen of the United States, residing at Tallassee, in the county of Elmore and State of Alabama, have invented a new, original, and ornamental Design for a Scarf, of which the following is a specification, reference being had to the accompanying drawing, forming part thereof.

The figure is a plan view of a scarf, showing my new design.

I claim:

The ornamental design for a scarf, as shown.
